UNITED STATES PATENT OFFICE.

JOHN W. MAILLOT, OF NORTH ATTLEBOROUGH, MASSACHUSETTS, ASSIGNOR
TO THE F. M. WHITING COMPANY, OF SAME PLACE.

DESIGN FOR A SPOON.

SPECIFICATION forming part of Design No. 25,259, dated March 24, 1896.

Application filed January 6, 1896. Serial No. 574,547. Term of patent 3½ years.

To all whom it may concern:

Be it known that I, JOHN W. MAILLOT, a citizen of the United States, residing at North Attleborough, in the county of Bristol and State of Massachusetts, have invented and produced a new and original Design for Handles for Spoons and Forks, of which the following is a specification.

In the drawings, Figure 1 represents a front or face view of a spoon, the handle of which contains the design. Fig. 2 shows a rear view of the spoon-handle.

Upon the face of the spoon and following the outline thereof the design is arranged and composed as follows: At the head of the handle A, upon its front face, is located a shell-like ornament of three parts, a portion of which conforms to the outline. On either side, extending about half-way down the handle, are compound ogee scrolls with beads 2, said scrolls ending in inwardly-curved portions extending toward each other. Below

this on either side are plain rows of beads extending downwardly along the outline to the end of the handle 3. On the rear face of the handle a shell-like scroll ornament is located at the top 4. On either side, extending down to the end of the handle and conforming to the outline, are rows of bands 5.

I claim—

The design for a spoon herein shown and described, consisting of the scroll on the front and back of the handle end, the plain lines of beads along the margin of the back, the lines of beads along the margins of the front from the end to the bowl and the ogee scroll interrupting the beads centrally thereof.

In testimony whereof I affix my signature in presence of two witnesses.

JOHN W. MAILLOT.
